UNITED STATES PATENT OFFICE.

GEORGE R. HANNON, OF IVESDALE, ILLINOIS.

RAILWAY-RAIL.

1,092,646.

Specification of Letters Patent.

Patented Apr. 7, 1914.

Application filed July 1, 1913. Serial No. 776,803.

To all whom it may concern:

Be it known that I, GEORGE R. HANNON, a citizen of the United States of America, residing at Ivesdale, in the county of Champaign and State of Illinois, have invented certain new and useful Improvements in Railway-Rails, of which the following is a specification.

This invention relates to railway-rails and 10 more particularly, to that form of rail the ends of which are adapted to interlock.

The objects of my invention are to provide a rail which may be easily and quickly laid; to do away with the use of fish-plates 15 and bolts; and to provide a rail which is in effect continuous, preventing the jarring or knocking usually experienced at rail joints.

With these and such other objects in view, as will hereinafter more fully appear, my 20 invention consists in the novel arrangement and construction of parts set forth in the description and claims, and which are shown in the accompanying drawings, wherein:—

Figure 1 is a perspective view of a rail 25 embodying my invention. Fig. 2 is a longitudinal sectional view showing the interlocking of the rail ends. Fig. 3 is a vertical sectional view of the interlocked ends.

Referring to said drawings by numerals, 30 a rail provided with the usual base 1 has said base thickened, near the end of the rail, as shown most clearly at 2. Said base, at the thickened portion thereof, is cut away on its upper surface, as shown most clearly 35 at 3, at one side of the rail web 4 and is under cut on the opposite side of said web, as shown most clearly at 5. The upper surface of said base, at the under cut portion thereof, has formed thereon a thickened portion 40 or rib 6 terminating near the rail web in a vertical face and forming, between said face and the web a slot 7. The web of said rail is likewise thickened near the end of the rail, and practically one-half the web 45 and ball 8 are cut away, at the end of said rail, leaving on said cut away side the wing web 9. The ball 8 of said rail is provided,

at the end thereof, with an overhang or apron 10, for the purpose of forming between it and the web 4 a slot for the reception of the upper edge of wing-web 9, the lower edge of which rests in the aforesaid slot 7. As will be readily understood, the ends of the rail are oppositely disposed counterparts of each other.

In practice my invention is operated as follows:—The rails are laid the ends being brought together, the wing web 9 enters the slot formed between the apron 10 and web 4, and the slot 7; the reduced end of web 4 of one rail end entering the recess between wing web 9 and web 4 of the other rail. The under cut base portion slides upon the over cut base portion and rests thereon. The rails are then spiked or otherwise fastened 55 in place.

Having described my invention, what I claim as new and desire to secure by Letters Patent, is:—

1. In a railway rail, a reduced ball and 70 web at each end thereof, a wing-web at each end of said rail, said wing-web being suitably spaced from said reduced web, a reduced base portion underlying said wing-web, and an under cut base portion integral 75 with said reduced web.

2. In a railway rail, a reduced ball and web at each end thereof, a wing-web at each end of said rail, said wing-web being suitably spaced from said reduced web, a reduced base portion underlying said wing-web, an under cut base portion integral with 80 said reduced web, said undercut base portion being provided with a groove in the upper surface thereof adjacent said reduced web, 85 and an apron on the aforesaid reduced ball portion of said rail.

In testimony whereof I hereunto affix my signature in presence of two witnesses.

GEORGE R. HANNON.
